UNITED STATES PATENT OFFICE

2,238,789

SEPARABLE BELT CONNECTOR

Manuel Castro, Canton, Ohio

Application May 12, 1939, Serial No. 273,285

9 Claims. (Cl. 24—196)

The invention relates generally to separable connectors for belts of any desired flexible material, and for any desired use, and more particularly to separable connectors for men's trouser belts.

A usual belt buckle includes a rectangular frame and a tongue pivoted on one end bar of the frame, and the tongue pivoting end bar being connected with one belt end. Another belt end, which in the case of a man's trouser belt is the other end of the same belt connected to the buckle frame, has formed therein a series of longitudinally spaced holes and is adapted for being inserted through the frame and receiving the tongue in one of the holes, and there is usually provided a loop on the belt through which the punched end is inserted after being engaged with the hook.

In such a usual man's trouser belt, after the belt is buckled, the punched end of the belt extending beyond the buckle forms a double belt layer at one side of the buckle, and tends to flap loose from the trouser loops through which the belt extends, and presents an unsymmetrical and unattractive appearance.

Various forms of frictional buckles for releasably engaging the ends of belts have been proposed, but in the use of such buckles there is likewise always present the loose belt ends beyond and buckles.

Various forms of relatively complicated separable belt connectors or fasteners have been proposed including separable interengaging members to each of which is secured a belt end, and by the use of which loose belt ends are avoided.

Such relatively complicated separable connectors heretofore available have been relatively difficult and costly to manufacture, have been excessively thick preventing satisfactory use in trouser belts, have not been adapted for inexpensive ornamentation, and have been relatively difficult and awkward to use.

The objects of the present invention include the provision of an improved separable belt connector of simplified construction, and adapted for economical manufacture.

Further objects of the invention include the provision of such a separable belt connector which may be made relatively thin for convenient use in a trouser belt.

Further objects of the present invention include the provision of an improved belt connector construction particularly adapted for attaining a

wide variety of ornamentation at a relatively low cost.

Further objects of the present invention include the provision of an improved separable belt connector adapted for convenient and easy use.

The foregoing and other objects are attained by the separable belt connectors, constructions, parts, combinations and sub-combinations, comprising the present invention, the nature of which is set forth in the following general statement, and preferred embodiments of which are set forth in the following description, and which are particularly and distinctly pointed out and set forth in the appended claims forming part hereof.

The nature of the improved separable belt connector of the present invention may be stated in general terms as including two separable members, one of which is a channel plate having a web and opposite side flanges, and the opposite channel side flanges have formed therein oppositely opening grooves, slots, or apertures, any of which may be termed a recess.

One end of the channel web is connected with one end of a belt, and in the case of a trouser belt, the other end of the belt is connected with the other separable member of the connector, and which includes a metal shank about which the end of the belt is wrapped.

The shank is provided at its opposite ends with hook heads or trunnions which abut against opposite sides of the belt, the heads or trunnions being adapted to be inserted in the grooves, slots, or apertures in the channel flanges by longitudinally angling the end of the belt having the hook heads or trunnions on it with respect to the channel web and then by twisting the hook headed shank and inserting the same between the channel flanges, and then by twisting the shank to insert the hook heads or trunnions into the opposite channel flange grooves, slots, or apertures. Reverse motions are used for unfastening the improved connector.

The present invention furthermore includes improved general and detail constructions, arrangements, and parts, as hereinafter set forth and claimed.

By way of example, a number of embodiments of the improved belt connector hereof and the parts thereof, are illustrated in the accompanying drawing forming part hereof, in which

Figure 1 is a front elevation of one embodiment of the improved belt connector hereof, shown in use on fragmentary belt ends, which may be the ends of a trouser belt;

Fig. 2, rear isometric views of the disassembled preferably metallic channel plate and interengagable shanks of the connector of Fig. 1, without any belt ends being wrapped around the shanks;

Fig. 3, a transverse sectional view of the channel plate thereof, as on line 3—3, Fig. 4, the shanks being removed;

Fig. 4, a longitudinal sectional view of the connector of Fig. 1 as on line 4—4, Fig. 3, showing at the left the one shank and associated belt end in place, and showing at the right the other separated shank in angled position ready for twisting so that its hook heads or trunnion ends may be engaged with the opposite channel flange grooves;

Fig. 5, a view similar to Fig. 4 after the trunnioned shank has been connected with the channel plate, as in Fig. 1;

Fig. 6, a horizontal sectional view thereof as on line 6—6, Fig. 5;

Fig. 7, a front elevation view of the channel plate only of a second embodiment of the improved belt connector, which may be metal or a plastic of one color such as yellow, and which is provided with an underlying insert which may be metal or a plastic of another color such as white;

Fig. 8, a side elevation thereof looking in the direction of the arrows 8—8, Fig. 7;

Fig. 9, a plan view of the channel plate only of a third embodiment of the improved connector hereof, which may be of metal or a plastic of one color such as white, and provided with an overlying gripping channel which may be of metal or a plastic of another color such as yellow.

Fig. 10, a side elevation thereof looking in the direction of the arrows 10—10, Fig. 9;

Fig. 11, isometric views similar to Fig. 2 of the parts of a fourth embodiment of the improved belt connector hereof.

Similar numerals refer to similar parts throughout the drawing.

The first embodiment of the improved belt connector hereof illustrated in Figs. 1 to 6 inclusive is indicated generally by 12 and includes a plurality of separable releasably interengagable members 13, 14, and 15. The connector member 13 is an improved channel plate having a web 16 and opposite side flanges 17 and 18 extending angularly from the opposite edges of one side face of the web, the side flanges 17 and 18 having formed therein respectively oppositely opening grooves or slots 19 and 20, the ends of which constitute end stops 21.

At one end of the channel plate 13 the flanges 17 and 18 are preferably connected by a clamp bar 22 which forms a rectangular collar with the flanges 17 and 18 and the web 16.

The separable member 14 as shown is an insert member of improved form and includes a flat shank 23 having enlarged hook heads or trunnions 24 and 25 on its opposite ends at one border. The other border of the flat shank 23 between the trunnions 24 and 25 is scalloped to form a central thumb and finger receiving notch 26.

The separable member 15 as shown is in the form of a square shank. The separable member 15 in use is normally permanently associated with the channel plate 13 and with one end 27 of a belt, such as a trouser belt, by angling the shank connector member 15 and inserting the same with its ends extending into the oppositely opening grooves 19 and 20, and by folding the ex-

tremity 28 of the belt end 27 about the shank 15, after having inserted the extremity 28 between the channel web 16 and the shank 15, and then inserting the folded extremity 28 backwardly upon the belt end 27 and between the shank 15 and the clamp bar 22, and then by pulling the folded or doubled belt end 27 and the shank 15 about which it is wrapped so that the ends of the shank 15 engage with the stop ends of the grooves 19 and 20 beneath the clamp bar 22 and so that the folded belt about the shank is wedged between the clamp bar 22 and the channel web 16 in the rectangular collar formed thereby with the flanges 17 and 18.

This arrangement of the channel plate 13 with its grooves 19 and 20 and clamp bar 22, and the shank 15 wrapped about by the belt end 27, provides an improved adjustable connection for the belt end 27 which is ordinarily not fastened in use, and which does not necessarily require that the folded extremity 28 of the belt end 27 shall be sewed to the belt end 27.

It is furthermore to be noted that the folded over belt extremity 28 is located at the rear of the belt end 27 when the improved connector 12 is used on a trouser belt.

The improved connector insert member 14 is associated in use with a belt end 29 which may be the other end of the trouser belt having the belt end 27.

The belt end 29 is wrapped around the shank 23 of the connector member 14 with the doubled extremity 30 of the belt end 29 at the same side as the extremity 28, as best shown in Fig. 6.

The doubled extremities 28 and 30 of the belt ends 27 and 29 respectively may be if desired glued, sewed or otherwise secured to the belt ends, but it is not necessary to secure the belt extremities since the improved connector when used on a trouser belt, maintains the wrapped around belt extremities 28 and 30 in any position of adjustments to which they are pulled.

In engaging the separated member 14 and its wrapped around belt end with the channel plate 13, the thumb and finger of the user grasps opposite sides of the wrapped around belt end 29 immediately adjacent the thumb notch 26. The connector member 14 and wrapped around belt end 29 are then angled to the position shown in Fig. 4, permitting insertion of the shank 23 and its hook heads or trunnions 24 and 25 between the channel flanges 17 and 18, after which the shank 23 may be twisted to a vertical position as shown in Fig. 5 in which the spacing of the hook heads or trunnions 24 and 25 is such to abut against the end stops 21 in the opposite grooves or slots 19 and 20.

Reverse motions are used in disengaging the separable trunnioned connector member 14 from the grooved channel connector member 13.

The hook heads or trunnions 24 and 25 are thicker than the shank 23 and protrude over the faces of the flat shank at one border and engage the sides of the wrapped around belt end 29.

The parts or members 13, 14, and 15 of the improved connector 12 are thus of relatively simple construction, and provide an efficient and satisfactory adjustable and separable belt connector.

The second embodiment of the improved connector hereof indicated generally by 112 in Figs. 7 and 8 is generally similar to the connector 12 but the channel plate 113 of the connector 112 may be formed of metal or a plastic of one color and have an ornamentally shaped web 116 with

an underlying ornamental insert plate 131 of metal or a plastic of another color.

The underlying insert plate 131 as best shown in Fig. 8 may be removably secured in auxiliary grooves 132 and 133 on the opposite inner faces of the channel flanges 117 and 118.

The third embodiment of the improved connector hereof illustrated in Figs. 9 and 10 is indicated generally by 212 and is generally similar to the connector 112, but in the connector 212 the channel plate 213 may be made of metal or a plastic of one color and is provided with an overlying ornamental gripping channel 234 which may be of metal or a plastic of another color, and may be ornamentally shaped.

The fourth embodiment of the improved connector hereof illustrated in Fig. 11 is indicated generally by 312 and is generally similar to the connector 12, but in the connector 312 the channel plate 313 has opposite flat side flanges 317 and 318, and in the side flange 317 there is formed a circular aperture or slot 335 and in the flange 318 there is formed an elongated slot or aperture 336 for receiving the trunnions 324 and 325 of the connector member 314, which has a plate shank 323 similar to the plate shank 23, but the trunnions 324 and 325 are laterally offset from the belt shank 323 to accommodate a folded belt end and permit the channel plate 313 to be relatively thin.

In the connector 312 the shank 315 is not removable, but has its ends permanently secured in suitable apertures formed in the flanges 317 and 318.

The apertures 335 and 336 of the channel plate 313 function in the same manner as the grooves 19 and 20 of the channel plate 13.

The embodiments of the present improvements illustrated and described herein are by way of example and the scope of the present invention is not limited to the same or to the particular details thereof, but is commensurate with any and all novel subject matter contained herein which may at any time properly under the patent laws be set forth in the claims hereof or originating herein, and the elements of any such claims are intended to include their functional or structural equivalents.

I claim:

1. In a separable connector for a belt and the like, two separable interengageable members, one of the members including a channel plate having a web and opposite side flanges, and there being oppositely opening recesses formed in the side flanges, the recesses having stop ends, and the other member including a shank having opposite ends adapted for being angled into the recesses in abutment engagement with opposite stop ends thereof, and the channel plate member furthermore including at one end thereof a clamp bar extending between the opposite side flanges and laterally spaced from the web and forming therewith a rectangular collar, and a second shank located between the clamp bar and the web and having its ends in engagement with the channel flanges.

2. In a separable connector for a belt and the like, two separable interengageable members, one of the members including a channel plate having a web and opposite side flanges, and there being oppositely opening recesses formed in the side flanges, the recesses having stop ends, and the other member including a shank having opposite ends adapted for being angled into the recesses in abutment engagement with opposite

stop ends thereof, and the channel plate member furthermore including at one end thereof a clamp bar extending between the opposite side flanges and laterally spaced from the web and forming therewith a rectangular collar, and a second shank located between the clamp bar and the web and having its ends in engagement with the channel flanges, each of the shanks having a belt end wrapped around it, the wrapped belt end on the second shank being clamped in the rectangular collar between the clamp bar and the web.

3. In a separable connector for a belt and the like, two separable interengageable members, one of the members including a channel plate having a web and opposite side flanges, and a clamp bar extending between the side flanges and being laterally spaced from the web and forming therewith a rectangular collar, and a shank located between the clamp bar and the web and having its ends engaged by the flanges, and a belt end wrapped around the shank and clamped in the rectangular collar between the clamp bar and the web.

4. In a separable connector for a belt and the like, a channel member and an insert member separably interengageable with each other, the channel member including a web and opposite side flanges extending angularly from the opposite edges of one side face of the web, the side flanges having formed therein opposite elongated slots which open towards each other, and the insert member including a flat shank having spaced borders with opposite trunnion ends at one border thereof, the trunnion ends being spaced for being angled into and out of engagement with the slots.

5. In a separable connector for a belt and the like, a channel member and an insert member separably interengageable with each other, the channel member including a web and opposite side flanges extending angularly from the opposite edges of one side face of the web, the side flanges having formed therein opposite elongated slots which open towards each other, and the insert member including a flat shank having spaced borders with opposite enlarged trunnion ends which are thicker than and which protrude over the faces of the flat shank at one border thereof, the trunnion ends being spaced for being angled into and out of engagement with the slots.

6. In a separable connector for a belt and the like, a channel member and an insert member separably interengageable with each other, the channel member including a web and opposite side flanges extending angularly from the opposite edges of one side face of the web, the side flanges having formed therein opposite elongated slots which open towards each other, and the insert member including a flat shank having spaced borders with opposite trunnion ends at one border thereof, the trunnion ends being spaced for being angled into and out of engagement with the slots, and a belt end wrapped around the flat shank.

7. In a separable connector for a belt and the like, a channel member and an insert member separably interengageable with each other, the channel member including a web and opposite side flanges extending angularly from the opposite edges of one side face of the web, the side flanges having formed therein opposite elongated slots which open towards each other, and the insert member including a flat shank having spaced borders with opposite enlarged trunnion ends which are thicker than and which protrude

over the faces of the flat shank at one border thereof, the trunnion ends being spaced for being angled into and out of engagement with the slots, and a belt end wrapped around the flat shank and the edges of the belt being engaged by the protruding trunnion ends.

8. In a separable connector for a belt and the like, a channel member and an insert member separably interengageable with each other, the channel member including a web and opposite side flanges extending angularly from the opposite edges of one side face of the web, the side flanges having formed therein opposite slots which open towards each other, one of the slots being circular and the other slot being elongated, and the insert member including a flat shank having spaced borders and trunnions at opposite ends of one of the borders, the trunnions being lat-

erally offset from the shank and being adapted for being angled into and out of engagement with the slots.

9. In a separable connector for a belt and the like, a channel member and an insert member separably interengageable with each other, the channel member including a web and opposite side flanges extending angularly from the opposite edges of one side face of the web, the side flanges having formed therein opposite slots which open towards each other, one of the slots being elongated, and the insert member including a flat shank having spaced borders and trunnions at opposite ends of one of the borders, the trunnions being laterally offset from the shank and being adapted for being angled into and out of engagement with the slots.

MANUEL CASTRO.
